LAMP MOUNTING FOR PHOTO-COPY MACHINES

John J. Johnson, Dallas, Tex.

Application August 6, 1935, Serial No. 35,017

1 Claim. (Cl. 240—1.3)

The present invention is directed to improvements in lamp mounting for photo-copy machines.

The primary object of the invention is to provide a device of this character so constructed that the lamps can be easily and quickly adjusted so that the rays therefrom may be directed properly on the work placed on the copy or engineer's board.

Another object of the invention is to provide a device of this kind wherein the mounting for the lamp is so constructed that the lamp can be swung laterally, moved vertically and tilted with respect to the copy board for effective operation.

Another object of the invention is to provide a device of this type which is movable with the copy board and adjustable at various angles with respect thereto in a simple manner.

With these and other objects in view, this invention resides in the novel features of construction, formation, combination and arrangement of parts to be hereinafter more fully described, claimed, and illustrated in the accompanying drawings, in which:

25 Figure 1 is a front view of the device.

Figure 2 is a side elevation.

Figure 3 is a sectional view on line 3—3 of Fig. 1.

Figure 4 is a detail view, partly in section of 30 one of the frames.

Figure 5 is a sectional view on line 5—5 of Fig. 2.

Referring to the drawings, 1 designates the stand having mounted thereon the camera 2, 35 said stand having attached thereto guide rods 3 upon which are slidably guided the sleeves 4.

Formed integral with the sleeves 4 are brackets 5 adapted to support the copy or engineer's board 6. The board 6 is vertically adjustable through 40 the medium of the screw shaft 7 which is threaded in the cross-bar 8. The construction thus far described is conventional.

Connected integrally with the sleeves 4 are webs 9 and to which are similarly secured the heads 45 10 in which are journaled the lower ends of the lamp supporting rods 11. Since the heads 10 are integral with the sleeves 4 it will be obvious that when the copy board 6 is elevated or lowered the heads 10, as well as the rods 11 will be similarly moved.

The usual Cooper-Hewitt lamps 12 are mounted in the reflectors or hoods 13, as customary.

In order to support the lamps at various angles with respect to the board 6 brackets 14 55 are employed, said brackets consisting of frames 15, preferably of triangular form. The frames have upon their rear ends vertically spaced and aligned sleeves 16 and 17 adapted to slidably engage the rods 11, the sleeves 16 having set screws 60 18 carried thereby for engagement with the rods

11 in order that the frames can be held in various positions of adjustment on said rods.

The lower bars of the frames are formed with horizontally aligned sleeves 19—19 in which are fitted the ends of a relatively long sleeve 20, the 5 purpose of which will later appear.

Slidable in the sleeves 20 are arms 21, the outer ends of which are formed with heads 22 having bores 23 therein and in which are engaged the shanks 24, said shanks being retained in place 10 by the nuts 25. Set screws 19' secure the arms 20 in adjusted positions.

The shanks terminate at their lower ends in plates 26 adapted to intimately engage the plates 27 carried by the castings 28 which are fastened 15 to the hoods 13 in any approved manner. The plates 26 and 27 are normally held in intimate binding engagement by thumb screws 29 which pass freely through the plates 26, but are threaded into the plates 27. The plates thus arranged 20 constitute clamps of such construction that upon manipulation of the thumb screws 29 the lamps may be tilted about the axes of the screws 29 in order that the rays therefrom can be projected on the copy board at varying angles. 25

Briefly the operation is as follows:

The board 6 is adjusted to the desired position and the work placed thereon, after which the hoods 13 and associated lamps may be adjusted relative to the board merely upon raising or lowering the frames 14 upon the rods 11, and since the rods 11 are rotatably mounted the lamps may be swung laterally and aligned with the board upon adjusting the shanks 23 in the heads 22. 30 Upon adjustment of the clamps constituted by the plates 26 and 27 the lamps may be tilted to 35 the desired angle with respect to the board.

From the foregoing it will be seen that I have provided a lamp support for photo-copy machines constructed and arranged in such manner that the use of separate stands for the lamps are not necessary, and that the supports are compactly arranged. 40

What is claimed is:

In combination with the copy board of a photo-copy machine, heads on the board and movable therewith, rods having their lower ends rotatably engaged in the heads, frames swingably and vertically adjustable on the rods, horizontally disposed arms adjustably connected with the frames and having heads on their outer ends, clamping devices each comprising a pair of plates, one plate of each pair having shanks thereon for rotatable adjustment in the heads of 50 the arms, lamp hoods fixed to the other plates and clamping screws connecting the plates for holding same in adjusted positions. 55
